APPARATUS FOR MANUFACTURING FLOOR MATS

Don R. Cotterman, Pontiac, Mich., assignor to Baldwin Rubber Company, Pontiac, Mich., a corporation of Michigan

Original application October 16, 1939, Serial No. 299,730. Divided and this application April 29, 1940, Serial No. 332,343

13 Claims. (Cl. 154—1)

This invention relates to apparatus for manufacturing surface coverings, such as floor mats, and is a division of my copending application, Serial No. 299,730, filed October 16, 1939.

One of the principal objects of this invention resides in the provision of a relatively simple, inexpensive apparatus embodying means for making composite mats having a surface covering sheet of vulcanizable material and having a sheet of pile fabric on the surface covering sheet.

Another object of this invention consists in the provision of apparatus having means for curving the sheet of vulcanizable material to the desired contour while the sheet of pile fabric is in position thereon and also having means for protecting the pile of the fabric during the curving operation.

A further feature of this invention resides in the provision of apparatus wherein both of the above mentioned sheets are formed to the shape of the contoured surface of a suitable form by subjecting the sheets to the action of a fluid under pressure and wherein the pressure of the fluid is prevented from matting the pile on the fabric by a sheet of carding material having rigid teeth or projections engageable with the sheet of fabric to space the pile on the latter from the adjacent surface of the form.

The foregoing, as well as other objects, will be made more apparent as this description proceeds, especially when considered in connection with the accompanying drawings, wherein:

Figure 1 is a perspective view of a vehicle body flooring covered with a mat formed by the apparatus constructed in accordance with this invention;

Figure 2 is a sectional view taken substantially on the plane indicated by the line 2—2 of Figure 1;

Figure 3 is a plan view of the molding form and illustrating a mat in association therewith;

Figure 4 is a sectional view taken substantially on the plane indicated by the line 4—4 of Figure 3;

Figure 5 is an enlarged sectional view of a portion of the construction shown in Figure 4;

Figure 6 is a fragmentary diagrammatic view illustrating one type of pressure chamber that may be employed with the apparatus forming the subject matter of this invention.

The mat forming the subject matter of this invention is especially designed for use as a covering for the irregular surface of a vehicle body floor, designated in Figures 1 and 2 by the reference character 10. The flooring 10 is illus-

trated as having a "hump" or "tunnel" intermediate the opposite side edges for the purpose of accommodating parts (not shown) of the vehicle driving mechanism, and it will be observed from Figure 1 that the mat is tailored to neatly fit the irregular floor surface.

In detail, the mat comprises a covering sheet 11 of vulcanizable material, such as rubber, and an insert 12 of a different material, such as pile fabric. The covering sheet 11 is fashioned with a depressed portion 13 forming a recess 14 in the top surface thereof. The depth of the recess 14 approximates the thickness of the pile of the fabric sheet 12 and the latter is secured 15 within the recess.

Upon reference to Figure 2, it will be noted that the pile fabric has a base 15 secured to the upper surface of the recess and is further provided with pile 16 projecting above the base to a position substantially flush with the top surface of the covering 11 surrounding the pile fabric. As will be more fully hereinafter set forth, the covering sheet 11 is cured against the surface of a form having a contour corresponding exactly to the surface contour of the floor to be covered by the sheet 11 and the pile fabric 12 is secured to the covering sheet during the curving operation so that both sheets will neatly fit the flooring surface.

It will also be observed from Figure 2 that a fibrous backing 17 may be secured to the covering sheet 11. This backing may be in the form of jute, flock or similar materials and is applied in a manner to compensate for the difference in elevation between the base of the recessed portion 14 of the covering sheet and the portions surrounding this recess.

Upon reference to Figures 4 and 5, it will be noted that the apparatus comprises a mold or form 18 having a sheet metal supporting plate 19 corresponding in contour to the shape of the flooring adapted to be covered by the mat and having a sheet 20 preferably of hard rubber secured to the top surface of the plate. The marginal edge portions of the plate 19 project beyond the adjacent edges of the sheet 20 and are return-bent to provide a continuous chamber 21 extending around the marginal edge of the sheet 20. The upper wall 22 of the chamber overlaps the top surface of the marginal edge portion of the sheet 20 and the interior of the chamber 21 communicates with the exhaust side of a suitable pump (not shown) through the medium of a conduit 23. As shown in Figure 4 a clearance 22' is provided between the flange 22 and the

adjacent surface of the sheet 20 to prevent any air trapped beneath the covering sheet 10 to escape.

The sheet 20 corresponds to the contour of the plate 19 and is provided with a recess 24 in the top surface thereof having an area corresponding to the area of the mat occupied by the pile fabric tread sheet 12. Supported within the recess 24 is a section of carding material 25 having a flexible base portion 26 suitably anchored in the recess and having rigid teeth or projections 27 projecting above the top surface of the sheet 20. The base 26 of the carding cloth possesses sufficient flexibility to permit the same to conform to the contour of the adjacent surface of the form and, in the present illustration, follows the contour of the portion of the form which corresponds to the "hump" in the flooring.

The base 26 of the carding sheet 25 is preferably formed of a heat resisting material, such as rubber or rubber substitutes, and a plurality of staples or closely spaced pins are suitably anchored in the sheet while the latter is in its uncured state to form the teeth 27. The length of the portions of the staples or pins extending above the carding sheet is slightly greater than the depth of the pile 16 on the fabric sheet 12 so that when the sheet 12 is positioned in an inverted position on the carding cloth (Figure 5), the pile 16 is, in effect, suspended in a manner to prevent matting of the pile against the form 18.

As will be more fully hereinafter set forth, form 18 is adapted to be supported in a chamber 28 shown diagrammatically in Figure 6 as comprising a base 30 and a cover 31 removably supported on the base 30. A suitable sealing strip 32 is secured to the base 30 and is channel shaped in cross section for receiving the marginal edge of the cover. The base is apertured to receive the suction conduit 23 and the cover is apertured to receive a fluid pressure supply conduit 29. The above construction is merely shown for the purpose of illustration and forms no part of this invention.

Operation

In actual practice, a pile fabric sheet of the proper size is placed on the teeth of the carding material in an inverted position so that the teeth of the carding material contacts the top surface of the base 15 of the pile fabric sheet. When positioned in this manner, the pile 16 on the fabric sheet, in effect, extends between the rigid teeth 27 of the carding material in the manner designated by the enlarged sectional view shown in Figure 5.

After the pile fabric sheet is properly positioned on the carding material, a sheet of vulcanizable material, such as uncured rubber, is placed over the mold form 18 with the marginal edge portions overlapping the continuous flange 22 and with the intermediate portion extending over the underside of the base 15 on the pile fabric in contact with the base. The mold form 18 is then located within the pressure chamber 28 and preheated fluid under pressure such as steam is introduced into the chamber through the conduit 29. The fluid under pressure is applied to the exposed surface of the uncured sheet in the manner designated by the arrows in Figure 4 and the pressure is sufficient to conform both the uncured covering sheet and the sheet of pile fabric to the contour of the top surface

of the mold form 18. Also, the fluid under pressure is preheated to vulcanize or cure the rubber sheet to the contour of the form which, as stated above, corresponds to the contour of the flooring. It may be pointed out at this time that the teeth 27 of the carding material possesses sufficient rigidity to withstand the pressure of the vulcanizing fluid medium applied to the uncured sheet and, accordingly, the pile 16 of the fabric sheet 12 is prevented from matting during the application of the vulcanizing pressure.

It has previously been stated that the carding sheet has a base portion 26 formed of uncured rubber or rubber-like material and that the pins or staples are secured in the base while the latter is in its uncured state. If desired, the carding sheet is positioned on the form while the base portion 26 is in its uncured state and is cured to the contour of the form during repeated use in forming the contoured mats.

In order to maintain the vulcanizable material in proper position on the contoured form prior to introducing the form into the pressure chamber 28 and at the same time exhaust any air that may be trapped between the adjacent surfaces of the form and vulcanizable material, the marginal chamber 24 is exhausted. As stated above, the marginal portions of the vulcanizable material extend over the flange 22 and the resulting suction effected through the chamber 24 provides an effective seal around the material. Accordingly, the material will accurately conform to the contoured surface of the mat under the pressure of the fluid medium in the chamber 28. It will, of course, be understood that any tendency for the suction action to draw the pile fabric sheet toward the contoured surface of the form is prevented by the rigid teeth 27 on the carding sheet 25.

During the interval the uncured sheet is vulcanized to the contour of the mold form 18, the base 15 of the pile fabric is permanently united to the adjacent surface of the uncured sheet. This may be accomplished by vulcanizing the uncured sheet directly to the base 15 or by applying a curing cement to the undersurface of the base prior to placing the uncured sheet of stock over the mold form 18. On the other hand, a bituminous binder may be employed, instead of cement, and, in such a case, a binder is selected which will become tacky during the vulcanizing temperatures. In any event, the pile fabric is secured in place on the sheet of vulcanizable material during the time the latter is cured to the contour of the mold form and this, of course, is desirable in that it not only reduces the cost of manufacture, but also appreciably expedites the time required to make the mat.

When the vulcanizing process previously referred to is completed, the mold form 18 is removed from the pressure chamber 28 and a mat is produced which corresponds exactly to the contour of the flooring to be covered thereby and which is provided with an insert of fabric pile. The backing material 17 is then cemented or otherwise suitably secured to the undersurface of the mat and the latter is ready for installation.

What I claim as my invention is:

1. In apparatus for manufacturing floor coverings, a form having a surface adapted to support a sheet of vulcanizable stock, a sheet of material positioned on said surface of the form and having a plurality of closely spaced rigid projections extending toward the sheet of vulcaniza-

ble stock, said projections adapted to support a sheet of pile fabric with the base of the fabric engaging the sheet of vulcanizable stock and with the pile extending toward the form between the projections, and means for curing the sheet of vulcanizable stock while in engagement with the base of the pile fabric sheet.

2. In apparatus for manufacturing floor coverings, a form having a contoured surface adapted to support a sheet of vulcanizable stock, a sheet of material positioned on the contoured surface and possessing sufficient flexibility to conform to the contour of said surface, a plurality of closely spaced rigid pins projecting from the second sheet of material toward the vulcanizable stock and adapted to support a sheet of pile fabric with the pile extending toward the second named sheet between the pins and with the base portions thereof engageable with the adjacent surface of the vulcanizable stock, and means for applying fluid under pressure on the surface of the vulcanizable stock opposite the surface adjacent the base of the pile fabric to urge both of the above mentioned sheets toward the contoured surface of the form, the rigidity of the pins being sufficient to prevent matting of the pile under the action of the pressure.

3. In apparatus for manufacturing a floor covering for a floor having a hump therein, a form having a contoured surface provided with a recess therein corresponding in size to the hump and adapted to support a sheet of vulcanizable stock, a sheet of material positioned on the contoured surface of the form over said recess and conforming in contour to said surface of the form, a plurality of closely spaced rigid pins projecting from said sheet of material toward the vulcanizable stock and adapted to support a sheet of pile fabric with the pile extending toward said sheet of material between the pins on the latter and with the base portion thereof engageable with the adjacent surface of the vulcanizable stock, and means for applying fluid under pressure on the surface of the vulcanizable stock opposite the surface adjacent the base of the pile fabric to urge both the vulcanizable stock and sheet of pile fabric in a direction toward the contoured surface of the form, the rigidity of the pins being sufficient to prevent matting of the pile under the action of the pressure.

4. In apparatus for manufacturing contoured mats, a form having a contoured surface adapted to support a sheet of stock, a strip of carding material secured to the contoured surface of the form and having rigid teeth adapted to support a sheet of pile fabric with the pile of the fabric extending toward the form between the teeth and with the base of the fabric contacting the surface of the sheet of stock facing the form, and means for urging the stock and sheet of pile fabric toward the form.

5. In apparatus for manufacturing contoured mats, a form having a contoured surface adapted to support a sheet of stock, a strip of carding material secured to the contoured surface of the form and having rigid teeth adapted to support a sheet of pile fabric with the pile of the fabric extending toward the form between the teeth and with the base of the fabric contacting the adjacent surface of the stock, and a vacuum chamber communicating with the joint between the stock and adjacent surface of the form to urge the stock and pile fabric in a direction toward the form.

6. In apparatus for manufacturing contoured

composite mats, a form having a contoured surface adapted to support a sheet of vulcanizable stock, a strip of carding material positioned on the contoured surface of the form and possessing sufficient flexibility to conform to the latter surface, rigid teeth extending upwardly from the carding material adapted to support a sheet of pile fabric with the pile extending downwardly toward the form between the teeth and with the base contacting the adjacent surface of the vulcanizable stock, and means for urging the vulcanizable stock in intimate contacting relationship with the form and with the base of the pile fabric, the teeth on the carding material being sufficiently rigid to counteract the action of the last named means and prevent matting of the pile fabric.

7. In apparatus for manufacturing contoured composite mats, a form having a contoured surface adapted to support a sheet of vulcanizable stock, a strip of carding material secured to the contoured surface of the form and having rigid teeth extending upwardly to support a sheet of pile fabric with the pile extending downwardly toward the form and with the base portion thereof contacting the adjacent surface of the vulcanizable stock, and means for applying a pre-heated fluid under pressure against the exposed surface of the vulcanizable stock to cure the latter to the contour of the form, the rigidity of the teeth on the carding material being sufficient to hold the pile fabric in spaced relation to the form against the action of said fluid pressure.

8. In apparatus for manufacturing floor coverings having a sheet of vulcanizable material and having a strip of pile fabric on said sheet with the pile extending upwardly from the top of the sheet, a form having a surface adapted to support a sheet of vulcanizable stock with a strip of pile fabric located between the stock and form in such a manner that the pile on the fabric sheet extends toward the form, and a sheet of carding material on the form opposite the sheet of pile fabric and having closely spaced rigid teeth extending between the pile of the fabric into engagement with the base portion of the fabric to prevent matting of the pile against the form.

9. In apparatus for manufacturing floor coverings having a sheet of vulcanizable material and having a strip of pile fabric on said sheet with the pile extending upwardly from the top of the sheet, a form having a surface adapted to support a sheet of vulcanizable stock with a strip of pile fabric positioned between the stock and the form in such a manner that the pile on the fabric extends toward the form, means for applying fluid under pressure on the surface of the stock opposite the surface adjacent the base of the pile fabric to urge the stock and pile fabric toward the form, and a sheet of carding material mounted on the form opposite the strip of pile fabric and having rigid teeth projecting between the pile of the fabric into engagement with the base portion of the fabric to prevent matting of the pile against the form by the action of the fluid pressure.

10. In apparatus for manufacturing floor coverings having a sheet of vulcanizable material and having a strip of pile fabric on said sheet with the pile extending upwardly from the top of the sheet, a mold form having a contoured surface and having closely spaced teeth projecting from the contoured surface with the free ends of the teeth lying in a plane parallel to the plane of the contoured surface of the form, said contoured sur-

face adapted to support a sheet of vulcanizable stock with a strip of pile fabric located between the stock and contoured surface of the form in such a manner that the pile on the fabric strip extends toward the form between the teeth projecting from the contoured surface of said form, and means for curing the vulcanizable stock to the contour of the form.

11. In apparatus for manufacturing floor coverings having a sheet of vulcanizable material and having a strip of pile fabric on said sheet with the pile extending upwardly from the top of the sheet, a form over which a sheet of vulcanizable material and a sheet of pile fabric are adapted to be placed with the pile fabric sheet interposed between the form and sheet of vulcanizable material and with the pile extending in a direction toward the form, means for applying heat under pressure against the top surface of the sheet of vulcanizable material to cure the latter, said means also operable to urge the sheet of vulcanizable material into intimate contact with the base of the pile fabric sheet and to urge both the sheets toward the form, and means operating independently of the pile for holding the base of the pile fabric sheet spaced above the form during the curing operation to prevent matting of the pile against the form by the heat under pressure.

12. In apparatus for manufacturing a floor mat having a hump therein, a form having a contoured surface provided with a recess of a size corresponding to the hump in the floor and over which a sheet of pile fabric is placed with the pile extending toward the contoured surface of

the form, said form also adapted to support a sheet of vulcanizable stock with a portion of the stock extending over the base of the pile fabric sheet, means for applying heat under pressure on the top surface of the sheet of vulcanizable stock to cure the latter, said means also operable to urge the vulcanizable sheet into intimate contact with the base of the pile fabric sheet and to also urge both sheets in a direction toward the form, and means operating independently of the pile for holding the base of the pile fabric sheet spaced above the form during the curing operation to prevent matting of the pile against the form by the heat under pressure.

13. In apparatus for manufacturing composite mats, a form over which a sheet of vulcanizable material and a sheet of pile fabric are adapted to be placed with the pile fabric sheet interposed between the form and sheet of vulcanizable material and with the pile extending in a direction toward the form, means for applying heat under pressure against the top surface of the sheet of vulcanizable material to cure the latter, said means also operable to urge the sheet of vulcanizable material into intimate contact with the base of the pile fabric sheet and to urge both of said sheets in a direction toward the form, and means on the form and engageable with the base of the pile fabric sheet to hold the base of the pile fabric sheet a sufficient distance above the form during the curing operation to prevent matting of the pile against the form by the heat under pressure.

DON R. COTTERMAN.
